UNITED STATES PATENT OFFICE.

WILLIAM C. CARR, OF BUFFALO, NEW YORK.

AUTOMATIC TRANSPORTING DEVICE.

No. 851,649.

Specification of Letters Patent.

Patented April 30, 1907.

Application filed September 17, 1906. Serial No. 334,884.

To all whom it may concern:

Be it known that I, WILLIAM C. CARR, a citizen of the United States, residing at Buffalo, in the county of Erie and State of New York, have invented a certain new and useful Improvement in Automatic Transporting Devices, of which the following is a specification.

This invention relates to an improved automatic transporting system, and the object of the invention is to provide means for economically delivering and collecting packages, mails or other articles to and from a series of stations, the mail delivering and collecting mechanism being independent of the package distributing and collecting mechanism.

The invention also relates to the construction of the car and the stations whereby a package or packages of irregular shapes and different sizes can be collected from one or more stations along the route of the car and carried to the central station from which the car begins its journey and to which it returns after having visited each station along its route.

The invention also relates to certain details of construction all of which will be fully and clearly hereinafter described and claimed, reference being had to the accompanying drawings, in which,—

Figure 1, is a side elevation of a car, one of the stations and a fragment of the track, showing the car approaching the station to collect a package. Fig. 2, is a view similar to Fig. 1, showing the car passing through the station and about to pick up the package, the front door of the package receptacle being open to admit the package. Fig. 3, is an enlarged side view of the car supported upon the track, the frame of the car being broken and a portion thereof omitted and the package receptacle also being broken and a portion thereof omitted. Fig. 4, is an enlarged transverse section through the track, showing an end view of a station and an approaching car. Fig. 5, is an enlarged top plan view of the car supported upon the track, a horizontal section being taken through the hood or cover to disclose the mechanism for opening the side door and ejecting the package. Fig. 6, is a top plan view on a reduced scale of the track and one of the stations. Fig. 7, is an enlarged fragmentary side view of the track near a station showing the construction of the rail to automatically reduce the speed of the

car. Fig. 8, is an enlarged fragmentary top plan view of the mechanism for opening the side door, the mechanism being shown in the position it assumes when passing through a station without delivering a package. Fig. 9, is a view similar to Fig. 8, showing the mechanism in the position it assumes when delivering or ejecting a package at a station. Fig. 10, is an enlarged section on line *a—a*, through the mechanism for opening the side door. Fig. 11, is an enlarged detached view of the slotted clutch member. Fig. 12, is an enlarged detached front view of the package receptacle with the front door removed, showing the side door closed in full lines, and open in dotted lines as when delivering a package.

In referring to the accompanying drawings for the details of construction, like numerals 75 designate like parts.

In the preferred form of the invention as illustrated in the drawings, the delivering and collecting car is supported upon a track which is elevated a suitable distance above 80 the ground. The car is operated by electric motors to which electricity is conducted by the rails forming the track. Stations are located at suitable points along the track to which deliveries are made and from which 85 packages can be collected and brought to the central station.

The rails.—The rails 1, forming the track, extend parallel to each other and are supported at the upper ends of U-shaped brackets 2, which are secured to the upper ends of vertical standards 3. The rails are preferably formed of angle-bars of the sectional form illustrated in Fig. 4, and are insulated from the brackets in the usual and well 95 known manner to prevent the short circuiting of the electric current.

The car.—The car consists of two parallel sides each of which is composed of two members, an upper member 5, and a lower member 6, which are separated sufficiently so as to leave a narrow space or slot 7, between them. The upper members 5, are connected by two transverse bars 8, and the two members 5 and 6, of each side are connected by vertical straps 9, so that the members 6, are vertically beneath the members 5. This frame is suspended from two axles 10, by curved straps 11, so that it hangs between and below the rails 1, the ends of the axles 110 having wheels secured thereto which ride upon the rails and support the car.

The car is driven by two rotary electric motors 12, which are mounted directly upon the axles 10, in the manner shown in Figs. 3 and 4. The electric current for operating the motors is taken from the rails 1, by trolley wheels 13, which are journaled in the upper ends of trolley arms 14, and travel on the under side of the rails 1, as shown in Fig. 4. These arms 14, are pivoted at their lower ends to metal plates 15, which are bolted against the outside of the upper members 5, of the car sides, but insulated therefrom. Springs 16, maintain the trolley wheels in contact with the rails.

15 Wires 17, conduct the current from the metal plates 15, to one of the motors and wires 18, connect the two motors in the well known and usual way so that but one set of trolleys need be employed.

20 The motors are inclosed within a box or cover 19, which is supported by angular metal bars 20, bolted to the transverse bars 8, see Figs. 3 and 4.

25 *Package collecting and delivering mechanism.*—The package collecting and delivering mechanism consists of a box-like receptacle having mechanism whereby a package may be automatically collected from one or more stations along the route of the car, and independent mechanism whereby a package which has been placed within the receptacle at the central station will be automatically delivered at any predetermined station along the route. The package receptacle is 35 mounted upon the body proper and is undetachably secured thereto forming a permanent portion of the car structure.

The package receptacle is preferably in the form of a rectangular box 21, constructed of 40 wood or sheet metal and as light as possible, consistent with the necessary strength and rigidity. In the form illustrated the box is made of wood and mounted upon the top of the motor box 19, being supported thereby, 45 see Figs. 3 and 4. It is provided with two swinging doors 22 and 23, located respectively at the front end and the side of the receptacle. The front door 22, which practically forms the entire front end of the receptacle is pivoted at its bottom to a horizontal rod 24, the ends of which are supported by horizontal metal bars 25, secured by screws to the sides of the receptacle. Vertical metal bars 26, are seated in and secured to 55 the vertical side edges of the door 22, with their lower ends projecting below the bottom edge of the door. These projecting ends have openings therein through which the rod 24 passes, thereby hinging the door to the receptacle, see Figs. 3 and 4. A torsion spring 60 27, encircles the rod 24, and normally maintains the door in a closed condition. The door 22, has a vertical arm 28, fastened to one of its vertical edges, said arm having a 65 roller 29, pivoted to its lower extremity by a

bolt. The purpose of this arm and roller will be hereinafter described.

The mechanism for operating the side door 23, and delivering a package is illustrated in Figs. 3, 4, 5, and Figs. 8 to 12, inclusive, to 70 which reference will be had in the following description. The side door 23, is hinged at its top to one side of the receptacle 21, by hinges 30, so as to swing outwardly as shown in dotted lines in Fig. 12. The mechanism for opening this door is located upon the top of the receptacle 21, and is particularly illustrated in Figs. 5, 8, 9, and 10. A metal plate 31, is sunk into the top of the receptacle 21, so that it is flush with said top, and secured 80 in place by countersunk screws. A metal disk 32, having a short, stout vertically projecting central spindle 33, is fastened to the metal plate 31, by countersunk screws, being located near the side of the receptacle 21, opposite the door 23. A comparatively large metal disk 34, is rotatively mounted upon the spindle 33, being supported upon the disk 32. This disk 34, has an annular series of equally spaced vertical openings 35, near 90 its outer edge, the number of openings being equal to the number of stations along the route of the car. In the present instance there are twelve openings in the disk, said openings being consecutively numbered from 1 to 12, each opening corresponding to the station bearing a like number. A ratchet 36, is rigidly secured in central position upon the upper surface of the disk 34, and a horizontal bell crank is fulcrumed or operatively 100 supported upon the spindle 33, above the ratchet 36, the whole being maintained in position by a nut screwed upon the upper extremity of the spindle see Fig. 10. The longer arm 37, of the bell crank extends laterally beyond the side of the receptacle opposite the door 23, and carries a roller 38, on a vertical pin or bolt 39, at its outer extremity. A pawl 40, is pivoted to the under side of the arm 37, of the bell crank and is adapted to 110 engage with the teeth of the ratchet 36. The pawl is held against displacement by a spring 41. The shorter arm 42, of the bell crank, extends rearwardly at about right angles to the arm 37, and carries a sliding bolt 43, 115 which forms one member of a clutch. The sliding bolt 43, is supported in horizontal position upon the top surface of the arm 42, and is partially inclosed within a box 44. The outer extremity of the arm 42, has a vertical 120 slot 45, formed therein, and a vertically depending pin 46, carried at the outer end of the bolt 43, passes through the slot 45, and into a slot 47, in a slotted cam-like clutch member 48. This slotted cam-like clutch member is pivoted to the inner end of a transverse sliding bar 49, which extends oppositely to the arm 37 of the bell crank, and projects beyond the side of the receptacle 21. A curved link 50, connects the outer ex- 130

tremity of the bar 49, to the side door 23, in the manner shown in Figs. 4 and 12. The bar 49, is slidably secured in place by straps 51, see Figs. 5, 8 and 9.

5 When the slotted cam-like clutch member is in its normal position, as shown in Fig. 5, the slot 47, is concentric with the edge of the disk 34, so that the pin 46, will ordinarily ride to and fro in said slot when the bell crank is 10 operated, without disturbing the position of the clutch member 48. However, when the station is reached where it is desired to deliver a package, the slotted cam-like clutch member 48, is automatically moved so that 15 the pin 46, will seat in a notch or pocket 52, therein and at the next movement of the bell crank, open the door 23 and eject the package. This is accomplished by means of a pin 53, which is adapted to be placed in any one 20 of the series of openings 35, the number of the opening corresponding to the number of the station at which the package is to be delivered. For instance if the pin is placed in the opening numbered "9" as in Fig. 5, 8 25 and 9, of the drawings, the package will be automatically delivered at the ninth station on the route of the car.

Each time the car passes through a station, the bell crank is moved from the position 30 shown in Fig. 5, to the position shown in Figs. 8 and 9, thereby giving the disk 34, one-twelfth of a revolution by means of the pawl 40, and ratchet 36. The bell crank is given this movement by a device located at each 35 station which will be hereinafter described.

When the car is between stations "6" and "7", the pin 53, will be in the position shown in Fig. 5. As the car passes through station "7", the bell crank assumes the position 40 shown in Fig. 8, and by means of the pawl and ratchet moves the disk 34, and the pin 53, one step onward. As the car passes through station "8", the pin 53, is moved another step in the same manner as above. 45 When the pin 53, makes this movement, it engages the oblique inner edge 54, of the slotted cam-like clutch member 48, and swings said clutch member outward on its pivot into the position shown in Fig. 8. As 50 the bell crank is returned to its normal position by the spring 55, the pin 46, at the outer end of the bolt 43, rides back in the slot 45, but owing to the altered position of the clutch member 48, the bolt 43, is partially 55 drawn out against the tension of an extension spring 56, secured at its ends to the inner end of the bolt and to a pin on the bell crank, see Fig. 10. When the bell crank reaches its normal position the spring 56, 60 draws the bolt 43, and seats the depending pin 46, in the notch or pocket 52. Owing to the contour of the inner edge of the clutch member 48, the pin 53, maintains said clutch member in its altered position and a coiled 65 extension spring 57, maintains the clutch

member 48, in operative contact with the pin. When the car passes through the next or ninth station, the bell crank is given its customary movement but the pin 53, being seated in the notch 52, cannot operate in the slot 70 45, but instead carries the clutch member 48, and therewith the bar 49, into the position shown in Fig. 9, thereby opening the door 23, as shown in dotted lines in Fig. 12.

A pawl 58, pivoted to the plate 31, by a 75 bolt, engages the ratchet 36, and prevents any reverse movement of the disk 34, said pawl being retained in operative position by a spring 59, see Figs. 5, 8 and 9.

The package is automatically ejected from 80 the receptacle by a vertical hinged leaf or blade 60, which is hinged at its horizontal top edge to the inner side of the wall of the receptacle 21, opposite the door 23. This blade 60, which is preferably made of thin stiff sheet 85 metal, is preferably of the same size as the door 23, and when said door is closed hangs in vertical position within the receptacle and lies closely against the side wall as shown in full lines in Fig. 12. A link or links 61, connect the blade 60, to the door 23, being pivoted thereto near their vertical edges so as not to obstruct the interior of the receptacle. When the door is opened to deliver a package as hereinbefore described the blade 60, 95 swings on its hinge into the position shown in dotted lines in Fig. 12, and gives the package a smart push or shove thereby ejecting it through the open door. As the door opens very rapidly owing to the speed at which the 100 car passes through the station the movement of the blade 60, is very sharp so that the package leaves the receptacle before the door resumes its normal or closed position.

A box or hood 62, incloses the mechanism 105 on top of the receptacle 21, and is secured to said top by hinges 63, so that it may be lifted to expose the mechanism within. Slots are formed in the sides of this box or hood to permit the operation of the bell crank and 110 the sliding bar 49, see Fig. 5.

The stations.—The stations of which there may be any number along the route of the car, are of similar construction and can be located at desirable points without regard to 115 the distances between them. One of these stations is illustrated in Figs. 1, 2, 4 and 6, to which reference will be had in the following description. The station comprises a vertical bar 64, which is bolted to one of the vertical portions of the U-shaped bracket 2, and a horizontal bar 65, secured to the upper extremity of the vertical bar 64. This vertical bar, which is located on the side of the track nearest the bell crank on the top of the car, is 120 bent outwardly near its upper end. The horizontal bar 65, extends parallel with the rails 1, of the track in a longitudinal direction, but in a slightly oblique manner transversely to said rails see Figs. 1, 2 and 6. An 125 130

inclined rail 66, is located at each station being supported from one of the rails 1, by blocks 67, and insulated therefrom in the usual manner. This inclined rail is placed outside of the rail 1, and extends parallel therewith in the manner shown in Fig. 6. A light transverse rod 68, is secured to one end of the horizontal bar 65, and extends horizontally over the track to about the middle thereof, and has its end bent so as to extend in a horizontal direction. The package or packages to be collected are supported from the longitudinal portion of the rod 68, by a string loop in the manner shown in Figs. 1 and 2, where the package is indicated by the numeral 69, and the string loop by the numeral 70.

As the car passes through the station, the front door 22, is opened to admit the package into the receptacle 21, by the roller 29, which rides upon the inclined rail 66, and gradually swings the door 22, on its pivot until it assumes the position shown in Fig. 2. The top of the box or receptacle 21, is provided with a deep V-shaped notch or depression 71, which catches the string loop 70, of the package 69, and removes the package from its supporting rod 68, permitting it to drop into the open end of the receptacle. The top edge of the end of the rod 69, is curved so as to permit the string loop to be easily disengaged therefrom. When the package has been collected, the roller 69, rides down the short steep inclined portion of the rail 66, and permits the spring 27, to rapidly close the door.

The bell crank located on the top of the receptacle 21, and which operates the mechanism for opening the side door 23, is operated by the roller 38, contacting with and riding along the oblique inner surface of the horizontal bar 65, which moves the longer arm 37, of the bell crank into the position shown in Figs. 8 and 9. This operates the mechanism as hereinbefore described.

The speed of the car is automatically reduced as it passes through the stations by means of raised portions 72, which extend for suitable distances on each side of the stations and taper down at their ends as shown in Fig. 7.

The wheels 73, mounted upon the ends of the axles 10, are formed as shown in Figs. 4, 5, and 7. Each wheel has two peripheries or treads of different diameters, the inner tread being approximately twice the diameter of the outer tread. A flange 74, is formed integral with each wheel and serves to retain said wheels upon the rails 1. The wheels are insulated from the axles by a core of insulating material to prevent the short circuiting of the electric current.

When the car is traveling between stations, the larger treads of the wheels 73, ride on the rails 1, causing the car to travel at a

comparatively high rate of speed. As the car nears a station, however the wheels strike the section of the track equipped with the raised portions 72, upon which the smaller treads of the wheels run, thereby raising the larger treads from the rails and reducing the speed of the car.

Mail collecting and delivering mechanism.—This car is also adapted to carry mail and other matter inclosed with boxes of uniform shape and size and to deliver and collect the same to and from the stations; said mail collecting and delivering mechanism being independent of the package delivering and collecting mechanism. In the construction embodied in the accompanying drawings, the car is so arranged with reference to the rails that the package collecting and delivering mechanism is located above the rails and forms the upper or top portion of the car, and the mail collecting and delivering mechanism below the rails in the lower or bottom part of the car. By this means the car is supported about midway with part of its load above and part of its load below the rails. The mail boxes are detachably supported from the body proper of the car and are detached from and attached to said body as the car passes through the stations to deliver and collect the mail to and from the stations. These boxes 75, have oppositely extending horizontal pins upon which rollers 76 are mounted, said rollers being adapted to enter the slot 7, between the frame members 5 and 6, of the car and support the boxes as shown in Fig. 4. The front and rear ends of the slots 7, are inclosed by dogs 77, and 78, the dogs 77, being automatically depressed by the entrance of a box and returned to their normal position by springs 105 to prevent the displacement of the box. The dogs 78, are operated by cam blocks 79, on the horizontal bars 80 of the stations, so that the last box on the car may be withdrawn from the slots 7, as the car passes through each station. Each station is supported by one of the U-shaped brackets 2, and consists of a U-shaped bar 81 secured to the bracket 2, by bolts as shown in Fig. 4. The horizontal bars 80, are secured to the upper ends of the vertical portions of the U-shaped bar 81.

When a large number of mail boxes are to be carried the car frame members may be lengthened as shown in Figs. 1 and 2, and the rear extreme of the car supported by straps 82, depending from an axle 83, having wheels 84, mounted upon its ends. Or the axles 10, may be separated sufficiently so as to equally distribute the increased weight of the lengthened car between them.

The operation of this improved transporting device is as follows,—The line is constructed on the loop system, that is beginning and ending at a central station from 130

which the car starts and at which it completes its run. When the operator at the central station receives notice, by telephone or other means that there is a package at one of the stations which is to be brought into the central station and sent on from thence to its destination, he starts the car upon its journey by applying electricity to the rails 1. The electric current is conducted to the motors 12, by the trolley wheels 13, trolley arms 14, metal plates 15, and wires 17 and 18, thereby causing the axles 10 to revolve. The door 22, is opened as the car passes through each station by the mechanism and in the manner hereinbefore described and when it reaches the station from which the package is to be collected, said package is received into the receptacle 21, in the manner shown in Fig. 2. The car continues its journey until it reaches the central station where the package is removed from the car and forwarded to its destination. When a package is received at the central station and is to be delivered to one of the sub-stations, the operator places the pin 53, in the particular opening 35, in the disk 34, which bears the number corresponding to the number of the station to which it is desired to make the delivery. The current is now applied to the rails 1, and the car begins its journey in the manner above described. When the predetermined station is reached the package is ejected in the manner heretofore described in detail, and the car completes its run to the central station.

A wire basket 85, or its equivalent is preferably located at each station to receive the packages as they are delivered, the basket being secured to the rails 1, as shown in Fig. 4, or secured in any suitable manner.

I claim as my invention—

1. In a transportation system, rails, a plurality of stations and a car supported from the rails having independent mechanisms for delivering and collecting mail and delivering and collecting packages.

2. In a transportation system, rails, a plurality of stations and a car supported from the rails having a mail delivering and collecting mechanism and a package delivering and collecting mechanism; said mechanisms being independently and automatically operated.

3. In a transportation system, rails, a plurality of stations and a car supported from the rails having two independent and automatically operable collecting and delivering mechanisms, one for packages and another for mail.

4. In a transportation system, rails, a plurality of stations and a car supported from the rails having an automatic mail collecting and delivering mechanism and an

independent automatic package collecting and delivering mechanism.

5. In a transportation system, rails, a plurality of stations, a car supported from the rails and having a mail collecting and delivering mechanism, a package receptacle separate from the mail collecting and delivering mechanism, and automatic mechanism for delivering a package from the package receptacle at any predetermined station.

6. In a transportation system, rails, a plurality of stations, a car supported from the rails and having a mail collecting and delivering mechanism, a package receptacle separate from the mail carrying mechanism provided with a front swing door and a package support located at one of the stations and adapted to support a package in position to be collected through said swing door as the car passes said station.

7. In a transportation system, rails, a station, a car supported from the rails, a package receptacle carried by said car, a separate independent mail collecting and delivering mechanism and automatic delivering and collecting means for the package receptacle.

8. In a transportation system, rails, a station, a car supported from the rails, a package receptacle carried by said car having a front collecting opening and a side delivering opening, a separate independent mail collecting and delivering mechanism and automatic delivering and collecting mechanism for the package receptacle.

9. In a transportation system, rails, a station, a car supported from the rails, a package receptacle carried by said car, a package support located over the rails and a package receiving tray located at one side of the rails, a separate independent mail collecting and delivering mechanism and automatic delivering and collecting mechanisms for the package receptacle.

10. In a transportation system, rails, a package support above the rails, a package receiver at one side of the rails, and a car supported from the rails and having a package receptacle mounted thereon and provided with a front opening for collecting from the package support and a side opening for discharging into the package receiver.

11. In a transportation system, rails, a package support, above the rails, a package receiver at one side of the rails, and a car supported from the rails and having a package receptacle mounted thereon and provided with a front swing door adapted to open to collect from the package support and a side swing door adapted to open to permit discharging into the receiver.

12. In a transportation system, rails, a station, a package support adjacent to the station located over the rails, a car supported

from the rails and having a package receptacle mounted thereon and provided with a front swing door and means for opening the door, whereby a package on the support is automatically picked up.

13. In a transportation system, rails, a station, a package support adjacent to the station, a car supported from the rails and having a swing door provided with an arm having a roller, and an inclined rail at the station upon which the roller is adapted to travel.

14. In a transportation system, rails, a station having a package receiver, a car supported from the rails and having a mail collecting and delivering mechanism and a separate package receptacle provided with a discharge opening and a swing door closing said opening and mechanism for opening said door and also discharging a package.

20 15. In a transportation system, rails, and a car having support from the rails and carrying an upper package receptacle and a plurality of lower mail receptacles which are independent of the package receptacle.

25 16. In a transportation system, rails, and a car having support from the rails and carrying an upper package receptacle and a plurality of lower separate independent individual mail receptacles.

30 17. In a transportation system, rails, a car having support from the rails and provided with an upper package receptacle and a plurality of detachable mail receptacles hung from the car beneath the package receptacle.

35 18. In a transportation system, rails, a car having support from the rails and provided with an upper comparatively large package receptacle and a series of small mail receptacles suspended beneath the package receptacle, a station, mechanism at the station for detaching a mail receptacle from the car and independent mechanism for collecting and discharging packages at the station.

45 19. A car having a skeleton body, a plurality of detachable individual mail receptacles depending from said body and an upper package receptacle mounted upon said body, mechanism for detaching and attaching mail receptacles to and from the car and independent mechanism for discharging and collecting packages.

50 20. A car having a skeleton body, a plurality of detachable individual mail recep-

tacles depending from said body and an upper package receptacle undetachably mounted upon said body, mechanism for detaching mail receptacles from the car and mechanism within the package receptacle for discharging packages therefrom. 55

21. A car having a skeleton body, a plurality of detachable individual mail receptacles depending from said body, an upper package receptacle undetachably mounted upon said body, automatic means for detaching mail receptacles from the car and 65 automatic means for ejecting packages from the package receptacle.

22. A skeleton car composed of two separated side members, a plurality of mail receptacles detachably supported between the side 70 members and an upper package receptacle permanently mounted on the car which is entirely independent of the mail receptacles.

23. A mail collecting and distributing car having a plurality of detachable individual 75 mail receptacles depending therefrom and a separate package receptacle permanently mounted thereon.

24. A combined mail and package collecting and distributing car comprising a skeleton frame between the members of which mail boxes are removably supported, and a separate package receptacle mounted on the skeleton frame. 80

25. A collecting and distributing car having a receptacle provided with a side ejecting opening and a front collecting opening. 85

26. In a transportation system, rails, a car supported by the rails and having a receptacle for packages provided with a front collecting opening and a support for packages located in proximity to the rails and adapted to support a package in the path of the car whereby a package on the support will be automatically picked up as the car passes. 90

27. A car of the class described, comprising a skeleton body composed of two parallel side members, a plurality of comparatively small receptacles depending between the members of the body and a separate comparatively large receptacle mounted permanently on said body. 95
